United States Patent

Des. 240,582
Patented July 20, 1976

240,582

TABLE

Ira Friedman, Somerset, N.J., assignor to Rowe
Furniture Corporation, Arlington, Va.

Filed Apr. 10, 1975, Ser. No. 567,020

Term of patent 14 years

Int. Cl. D6—03

U.S. Cl. D6—177

FIG. 1

FIG. 2

FIG. 3

FIG. 4

FIG. 5

FIG. 6

FIG. 7

FIG. 1 is a perspective view of the inventive table shown in the form of a chow table or lamp table;

FIG. 2 is an end view of the table illustrated in FIG. 1;

FIG. 3 is a top plan view of the table illustrated in FIG. 1;

FIG. 4 is a perspective view of the table illustrated in FIG. 1, shown in the form of a sofa table;

FIG. 5 is a perspective view of the table illustrated in FIG. 1, shown in the form of a rectangular cocktail table;

FIG. 6 is a perspective view of the table illustrated in FIG. 1, shown in the form of an end table; and

FIG. 7 is a perspective view of the table illustrated in FIG. 1, shown in the form of a square cocktail table.

I claim:

The ornamental design for a table, substantially as shown.
